UNITED STATES PATENT OFFICE

171,803

BUFFET BOWL

Warren E. Lawrence, Jr., Riverside, R. I., assignor to Gorham Manufacturing Company, Providence, R. I., a corporation of Rhode Island

Application September 14, 1953, Serial No. 26,777

Term of patent 7 years

(Cl. D44—15)

To all whom it may concern:

Be it known that I, Warren E. Lawrence, Jr., a citizen of the United States of America, residing in Riverside, State of Rhode Island, have invented a new, original, and ornamental Design for a Buffet Bowl, of which the following is a specification, reference being had to the accompanying drawings, forming a part hereof.

Fig. 1 is a top plan view of a buffet bowl, showing my new design;

Fig. 2 is a side elevational view; and,

Fig. 3 is a vertical sectional view thereof.

I claim:

The ornamental design for a buffet bowl, as shown.

WARREN E. LAWRENCE, JR.
